ELECTRICAL FACIAL MASSAGER OR SIMILAR ARTICLE

Samuel L. McNair, Whitman, Mass.

Application May 21, 1959, Serial No. 56,019

Term of patent 14 years

(Cl. D83—1)

FIG. 1.

FIG. 2.

FIG. 3.

FIG. 4.

Fig. 1 is a front elevational view of an electrical facial massager or similar article, showing my new design,

Fig. 2 is a left side elevational view,

Fig. 3 is a top plan view, and

Fig. 4 is a bottom plan view thereof.

This application is a continuation-in-part of my co-pending application D. 50,101, filed March 19, 1958, and now abandoned.

I claim:

The ornamental design for an electrical facial massager or similar article, substantially as shown.
